UNITED STATES PATENT OFFICE.

FREDERICK C. ROCKWELL, OF HAMILTON, ILLINOIS.

DISTRIBUTING-VALVE FOR BATH-TUBS.

1,037,664.

Specification of Letters Patent. Patented Sept. 3, 1912.

Application filed October 15, 1910. Serial No. 587,264.

To all whom it may concern:

Be it known that I, FREDERICK C. ROCKWELL, citizen of the United States, residing at Hamilton, in the county of Hancock and State of Illinois, have invented certain new and useful Improvements in Distributing-Valves for Bath-Tubs, of which the following is a specification.

This invention relates to the class of baths and closets, and pertains especially to a water distribution attachment for bath tubs.

The object of the invention is to provide novel and peculiar means for utilizing the waste water of bath tubs whereby such water may be directed from the tub to various places and for various purposes, such as irrigation, kitchen use, and similar purposes.

In certain localities water is so scarce every precaution is used to save the water as much as possible, and in order to provide for the same body of bath water being used more than once and for various purposes, I provide the bath tub with a device for discharging the water, after bathing, in various directions as desired or as occasion may demand.

The invention consists in the novel and peculiar construction and arrangement of parts, and especially in the attachment whereby water from bath tubs, after bathing, may be distributed in various directions from the tub; and means for controlling such distribution as desired.

Various other objects, and advantages, and desirable results are attainable in the practical application of the invention.

In the accompanying drawings forming part of this application:—Figure 1 is an elevation, partly broken away, showing the application of the invention. Fig. 2 is a vertical sectional view. Fig. 3 is a cross section taken through the valve chamber or casing, taken on the dotted line $\alpha-\alpha$ Fig. 1. Fig. 4 is a perspective view of the indicator wheel and nut. Fig. 5 is a side elevation, partly broken away, showing a modification. Fig. 6 is a section view of the modification.

The same reference numerals denote the same parts throughout the several views of the drawings.

The usual stand pipe 1, of an ordinary bath tub 2, is employed in carrying out this invention, and said pipe is connected to the drain-discharge 3, and the over-flow dis-

charge 4, of the tub by pipes 5 and 6 respectively.

The bottom of the pipe 1 is provided with one-half 7, of a casing and the other half 8, of the casing has a sewer or waste pipe 9, 60 and a distributing pipe 10 attached thereto and discharging from the water chamber formed by the casing. A valve-stem 11, has one end thereof journaled centrally in the casing portion 7, and it is cushioned by 65 means of a spring 12. A disk-valve 13 is secured to the stem 11, and works on the bottom of the casing portion 7, and is cushioned in its bearing thereon by the said spring 12. The disk 13 has a port 14, and a stop pin or lug 15, for engaging a pair of stop pins or lugs 16 on the casing portion 7, so as to limit the rotary movement of the disk, and stop it with its port over one or the other of the pipes 9 and 10, and thereby 70 open and close communication between the chamber and these pipes, according to the desired direction for the discharge of the water from the tub. The valve-stem 11 extends through the pipe 1, and through a 75 hand-wheel 17, having inscribed thereon the nature of the pipes 9 and 10, and the wheel is secured to the top of the pipe 1, by a boss 18. The stem 11 is turned by a nut 19, having an indicator finger or point 19, co- 80 operating with said inscriptions for indicating the position of the valve or disk 13.

Referring to the modification shown in Figs. 5 and 6, the valve disk 20, is provided with peripheral teeth which mesh with a 90 gear 21, inclosed in a gear-housing 22 secured to or forming a part of the valve casing 23. A shaft 24 is journaled in the housing 22, for operating the said gear and the disk. The casing 23 may have three or more distributing pipes 25, branched therefrom, and the disk may be operated by the gear to place the disk-port 26 over either of said pipes as desired. Obviously this casing and disk have no stop-lugs.

Flexible hose or other pipe may be attached to certain of the distributing pipes to carry the water from the bath tub to such place or places as desired, for example for watering lawns, kitchen use, stable use, and for various other purposes.

It will be seen that the device, in either form, is readily attached to ordinary bath tubs, and that the drain and over-flow are employed in the usual way.

110

I do not wish to be understood as limiting myself to any special size or material; to the number of distributing pipes; to the particular place in the stand pipe for applying the disk-valve; nor to the means for operating the valve as far as lies within the scope of this invention.

Having thus described my invention, what I claim as new and desire to secure by Letters Patent is:—

A water distributing attachment for bath tubs, comprising a two-part casing forming a water chamber, a water conducting pipe having the upper of said casing parts formed thereon with a pair of induction ports in the pipe above the casing, a plu-

rality of eduction pipes leading from the chamber and having the lower of said casing parts formed thereon, an operating stem extending through said pipe and through both parts of the chamber casing, a port disk formed on the stem and seated on the eduction pipes within the chamber, and means contained within the chamber for controlling the movement of the disk, substantially as and for the purpose set forth.

In witness whereof I hereunto set my hand in the presence of two witnesses.

FREDERICK C. ROCKWELL.
